ATTORNEY

UNITED STATES PATENT OFFICE.

SAMUEL TUTTLE SHEPHERD, OF ALBANY, NEW YORK.

DISPLAY-STAND.

1,351,007.

Specification of Letters Patent. Patented Aug. 24, 1920.

Application filed February 19, 1919. Serial No. 277,937.

To all whom it may concern:

Be it known that I, SAMUEL T. SHEPHERD, a citizen of the United States, residing at Albany, in the county of Albany and State 5 of New York, have invented a new and useful Display-Stand, of which the following is a specification.

This invention relates to display stands, and the object is to provide a device capable 10 of securely holding a cane, umbrella, flag or analogous article in upright position for display purposes.

Another object is to provide a holding means for the purpose stated, which will 15 permit of the introduction of different sized staffs of articles to be displayed and to effectually prevent any wabbling or swaying motion of the same while being held by the stand, at the same time permitting of the 20 ready removal of the device, together with the article being held, to another location when desired.

A full and complete understanding of the 25 invention may be obtained from a consideration of the following detailed description, taken in connection with the accompanying drawing forming a part of this specification; it being understood that while the drawing shows a practical form of the 30 invention, the latter is not confined to strict conformity therewith, but may be changed or modified, so long as such changes or modifications mark no material departure from the salient features of the invention, 35 as specifically pointed out in the accompanying claims.

In the drawing, in which like reference characters designate corresponding parts throughout the several figures:—

40 Figure 1 is a perspective view of the improved display stand.

Fig. 2 is a vertical central sectional view thereof and

45 Fig. 3 is a horizontal sectional view, taken on the line 3—3 of Fig. 2.

The invention comprises a base member 1 preferably in the form of a metal casting and preferably shaped in a bell or pear formation, as illustrated in the drawing, 50 though any other desired shape may be employed. The base member 1 is designed to have sufficient weight and breadth of base to prevent the cane, umbrella or other article being held in the device from toppling 55 over, thus insuring its stability.

The base member 1 is provided in its apex with a relatively wide recess 2 extending substantially half-way through the same in a vertical direction and terminating in a horizontally disposed bottom wall 3. 60 This bottom wall is counterbored for a short distance, as at 4, the said counterbore being of a diameter somewhat less than the diameter of the bore 2 and capable of receiving the ferrule end of a cane or walking-stick (not shown), the depth of said counterbore 4 being sufficient to prevent the end 65 of said cane from becoming unseated by accident.

A second counterbore 5 of still smaller 70 diameter than the counterbore 4 is provided in the base and extends from the bottom of the said counterbore toward the bottom of the base 1. This second counterbore is capable of receiving the ferrule end of a metallic 75 umbrella rod or staff and, in conjunction with parts presently to be described, and which parts also co-act with the counterbore 4, serves to support said umbrella in an upright position. 80

By reason of the counterbore 4, the bottom wall of the relatively wide recess 2 is in the form of an annular shoulder having, at points substantially midway between the wall of the bore 1 and the counterbore 4, diametrically opposed slots 6, arranged in two opposite pairs at right-angles to each other, and of a depth sufficient to receive and securely hold against movement, opposed clamping members 7, in the form of flat 85 metal strips of a thickness and width to be driven into the said slots and retained therein against accidental dislodgment. 90

The clamping members or strips are bowed inwardly toward the center of the 95 base member 1, as at 7^a to produce a contracted throat between the several members for the purpose of hugging the cane or umbrella, as will be readily understood, and the upper free ends 8 of said strips are flared 100 outwardly to provide a relatively wide entrance opening in order to facilitate the introduction of the article to be held by the device.

A stout rubber band or two, as indicated 105 at 9 in the drawing, are placed around the throat portions of the clamping members to assist in drawing them together to exert a clamping action on the article held. Instead of these bands one or more contin- 110

uous coiled springs may surround the said clamping members. On the other hand, such surrounding bands may be entirely dispensed with, and the clamping members be formed of spring metal which, of their own tendency, will exert the necessary inward pressure upon any article forced down between the same.

The device may be readily moved to the desired location, whether upon a floor or upon a shelf or show-case, and the umbrella or cane may be easily placed in the same by a slight pressure downwardly to force the clamping members apart and allow the ferrule end of the staff to be seated in the appropriate counterbore within the base member. Should the diameter of the article supported be greater than the diameter of the first counterbore, it will be confined between the lower ends of the clamping members where entering the base member and thus prevented from any lateral play, while other articles having a diameter between the diameters of the two counterbores will find only a limited amount of play before striking the wall of the first counterbore, which play will be insufficient to permit the overbalancing of the said article. The second or smaller counterbore is calculated to hold and prevent excessive lateral play of metallic umbrella ferrules or smaller articles.

What is claimed is:—

1. A display stand for holding canes, umbrellas or like articles, comprising a base member provided with a vertically disposed recess, flexible thin, flat clamping members mounted in the bottom wall of the recess and extending upwardly above the open end of the same and there flared outwardly to form an entrance opening between the same, means for constraining the members toward each other, and a plurality of counterbores of diminishing diameters communi-

cating with the bottom of the recess for receiving the ends of said articles.

2. A display stand for canes, umbrellas and the like comprising a base member provided with a vertical, longitudinal recess, upright clamping members mounted in the bottom wall of the recess and extending upwardly in spaced relation to the sides of said recess and beyond the upper end thereof, the ends of the same being flared outwardly, flexible bands surrounding the clamping members to force them together, and a counterbore extending from the bottom wall of the recess for the reception of the cane or umbrella staff.

3. A display stand for the purpose described, comprising a base member provided with a vertical longitudinal recess, upright clamping members mounted in the bottom wall of the recess and extending upwardly in spaced relation to the sides of said recess and beyond the upper end thereof, the upper ends of the same being flared out, and flexible bands surrounding the clamping members to force them together.

4. A display stand for the purpose described, comprising a base member, provided with a vertical, longitudinal recess, upright clamping members secured within the recess and extending upwardly in spaced relation to the sides of said recess and beyond the upper end thereof, the upper ends of the same being flared out, and means connected with the clamping members for forcing them together.

In testimony that I claim the foregoing as my own, I have hereto affixed my signature in the presence of two witnesses.

SAMUEL TUTTLE SHEPHARD.
